MOSES LEAVITT AND AZARIAH FOSTER, OF OTTAWA, ILLINOIS.

Letters Patent No. 78,975, dated June 16, 1868.

IMPROVED WASHING AND WRINGING-MACHINE.

The Schedule referred to in these Letters Patent and making part of the same.

TO ALL WHOM IT MAY CONCERN:

Be it known that we, MOSES LEAVITT and AZARIAH FOSTER, of Ottawa, in the county of La Salle, in the State of Illinois, have invented a new and improved Washing and Wringing-Machine; and we do hereby declare that the following is a full and exact description thereof, reference being had to the accompanying drawings, and to the letters of reference marked thereon.

The nature of our invention consists in constructing a washing and wringing-machine on a cheap and simple plan, the operation of which is easily understood by any person, and which can be constructed by any ordinary mechanic without the help of machinery.

Our invention also consists in a certain combination of an extra roller, by which the machine can be used both for washing and wringing, thus dispensing with the cost and incumbrance of a separate wringer.

To enable others skilled in the arts to make and use our invention, we will proceed to describe its construction and operation.

Figure 1 in the drawing is a horizontal plan.

Figure 2 is a vertical section through *a b*, fig. 1.

Figure 3 is a view of the lever, with rollers attached.

We construct a tub, *A*, of boards, jointed together water-tight, and the front part slanting upwards. Inside of this tub *A* are fastened two slide-ways, *B B*, in which slides the lever *C*, fig. 3. This lever *C* is made of two arms, *d d*, one cross-handle, *e*, one smooth roller, *f*, one bucket-roller, *g*, and of a brace, *h*.

At the ends of the arms *d d* are the blocks *o o*, which are the parts that engage between the ways *B B*.

Each of the rollers *f* and *g* is supported by springs *j j* and *k k*. At each of the blocks *o o* are attached staples, to which are linked the brass wires *l l*, and to these brass wires are attached the elastic cords *m m*, which pass over the grooved pulleys *D D*, and are fastened under the tub at *E*. Inside of the tub *A* is adapted the elastic board *F*, which is fastened at the forward end only, the rear part being made to rise and come down on to a cross-piece, *G*, by the pressure of the lever *C*. In said elastic board *F* is also cut a series of slots, into which movable slats *n n n* are inserted, hinged at *i*, and which receive a pressure upwards by the springs *q*. The object of this combination of the slats *n n n* and springs *q* with the board *F* is to compensate for inequalities in the thickness of the clothes to be washed; as the slats *n n n* will always press up the clothes against the roller.

To operate the machine, the tub *A* is filled with suds up to the lowest part of the elastic board *F*, the lever *C* is inserted, with the bucket-roller down, as shown in the drawings, the elastic cords *m m* being passed over the pulleys *D D*.

The machine will then be ready for washing, which operation is performed by pushing the bucket-roller *g* down past the elastic board *F*, and then pulling suddenly back, which motion is assisted by the action of the elastic cords *m m*. The suds will lodge in the buckets of the roller *g*, which suds will then spread over the clothes on the elastic board *F*. The roller *g* is then passed over the clothes, giving pressure with the lever *C*, and occasionally dipping out more suds with the buckets of the roller *g*, until the clothes are clean.

When the machine is to be used for wringing, the lever *C* is turned upside down, which brings the smooth roller *f* in contact with the elastic board *F*. The clothes are then laid on the said board, and the roller *f* passed over them, giving pressure by means of the lever *C*, when the water will be effectually pressed out of the clothes.

What we claim as our invention, and desire to secure by Letters Patent, is—

The smooth roller *f*, in combination with the bucket-roller *g*, the arms *d d*, the springs *j j*, and the springs *k k*, substantially as described.

2. The hinged slats *n n n* and the springs *q*, in combination with the elastic board *F*, substantially as and for the purpose described in the foregoing specification.

MOSES LEAVITT,
AZARIAH FOSTER.
